Primary Examiner—Daniel D Bui*Assistant Examiner*—Thomas J Johannes(74) *Attorney, Agent, or Firm*—Bell, Boyd & Lloyd LLP(57) **CLAIM**

We claim the ornamental design for a vehicle electrical center assembly, as shown and described.

DESCRIPTION

FIG. 1 is a perspective view of a vehicle electrical center assembly, showing our new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom view thereof showing an unclaimed alternate bottom usage environment.

The broken line portions shown in each of the figure drawings is included to show unclaimed subject matter only and forms no part of the claimed design.
